STRAND DISTRIBUTOR

**John A. Whitaker, Oak Park, Ill., assignor to
Western Electric Company, Incorporated, New
York, N. Y., a corporation of New York**

Application November 8, 1930. Serial No. 494,228

4 Claims. (Cl. 242—158)

This invention relates to strand distributors, and more particularly to a strand distributor for use in the winding of electrical coils.

The primary object of this invention is the provision of an improved distributor for a strand winding machine which will insure the accurate distribution of the strand to produce uniformly wound layers thereof.

10 In accordance with one embodiment of this invention as applied to a winding machine for producing electrical coils of the paper filled type, there is provided a strand distributor engaging the periphery of and reciprocable of the coil and movable outwardly therefrom during the winding
15 thereof in a single definite path in response to the increasing diameter of the coil with each layer of strand wound thereon. Specifically, the distributor comprises a strand guide carried by a vertically sliding bar upon which is journaled a
20 roller which engages the periphery of the rotating coil while being reciprocated to and fro along the coil by suitable traversing mechanism, the strand guide being mounted within the circumference of the roller and adjacent the periphery of the
25 coil. The bar is slidably mounted so as to permit movement of the roller in a single definite rectilinear path away from the axis of the coil to accommodate the increasing diameter of the coil as successive layers of strand are wound
30 thereon and thereby causing the guide, due to its single definite movement with the roller and the bar, to deliver the strand to the coil in uniformly wound layers. Also the bar is frictionally maintained, by a brake mechanism, in any position
35 relative to the axis of the coil to which it may be moved, the brake mechanism permitting the guide carrying bar to be moved in accordance with the increasing diameter of the coil, or to be moved manually into or out of its operative position with respect to the coil, and maintaining it in the position to which it is moved.

Other objects and advantages of this invention will more fully appear from the following detailed description, taken in connection with the accompanying drawing, wherein

Fig. 1 is a front elevation of a strand distributor embodying the features of this invention arranged in operative relation to a coil being wound, the latter being shown fragmentarily in dotted outline;

Figs. 2 and 3 are side and plan views, respectively, of the distributor illustrated in Fig. 1:

Fig. 4 is an enlarged detail fragmentary sectional view of a portion of Fig. 2, and

55 Figs. 5 and 6 are enlarged detail vertical and

horizontal sections taken on the lines 5—5 and 6—6, respectively, of Fig. 2, showing strand guiding fingers of the distributor in detached relation therewith.

Referring now to the drawing in detail, the numeral 10 indicates a traversing rod controlled by a reciprocating mechanism (not shown) whereby the rod is reciprocated longitudinally of the axis of rotation of a core 11 or a coil 12, shown fragmentarily in dotted outline (Figs. 1 and 2) for the purpose of distributing wire 13 in adjacent helices upon the rotating coil. The reciprocating mechanism and the means for supporting and rotating the coil may be of a well known type and therefore a detailed disclosure and description thereof are not considered necessary, since they form no part of the present invention.

shoe being spaced from the corresponding ends of the slot 25. The upper end surface of the shoe 27 (Fig. 4) is at one side formed with a raised portion 28 which extends inwardly from its outer edge to a point slightly within the smaller or lower diameter of the aperture 23 formed in the bar 20, the pivotal point 26 of the shoe 27 occurring adjacent its opposite side. Slidably fitted in the lower end of the aperture 23 of the bar 20 is a plunger 29 which engages the raised portion 28 of the pivotal shoe 27 and which is pressed downwardly into engagement with the portion 28 of the shoe 27 by a compression spring 32 positioned in the aperture 23. Compression of the spring is made variable by a hand screw 33 thread-
100
105
110

ed into the upper end of the aperture and engaging the upper end of the spring.

It will be evident that the pressure of the spring pressed plunger 29 against the raised portion 28 of the pivotal shoe 27 will at all times tend to rock the shoe about its pivot 26 in a counterclockwise direction to cause an engagement of the right side thereof with the adjacent surface of the lower arm 19 of the bracket 16, and due to the frictional contact therebetween the bar 20 will be maintained in any vertical position to which it is moved upon the bracket during the operation of winding the coil 12 in a manner to be described hereinafter. Furthermore due to the accurate mounting of the bar 20 in the arms 19 of the bracket 16 and the action of the spring pressed shoe 27 no movement of the bar other than its movement in a vertical definite rectilinear path can occur. This insures a very accurate delivery of the wire 13 during the winding operation.

The lower end of the bar 20 is provided with a slot 34 intermediate its sides (Fig. 1), in which is mounted two spaced wire guide plates 35 and 36, a spacing block 39 being entered therebetween. Upon opposite sides of the bar 20 at its lower end are similar roller and sheave supporting plates 40, which are secured in position together with the guide plates 35 and 36 and the spacing block 39 by a pair of bolts. Rotatably journaled between the plates 40 upon arms 42 thereof is a roller 43 formed with flanges 46 which roll upon the periphery of the coil 12 during the winding operation. Also rotatably journaled between the plates 40 upon arms 47 thereof is a wire guiding sheave 48, the roller and sheave being centered with the wire guiding space provided between the spaced plates 35 and 36 (Fig. 1). The forward or left end of the plates 35 and 36 as viewed in Figs. 1 and 2, respectively, are similar in shape and extend between the flanges of the roller 43 and clear the smaller central circumference of the roller.

At their extreme lower forward ends the plates 35 and 36 are shaped to provide wire distributing or guiding fingers 49, the fingers being bent inwardly to lessen the space between the plates at this point to substantially the diameter of the wire 13 which is to form the coil 12, thereby providing a comparatively short distance along the opposite surfaces of the fingers with which the traveling wire is closely associated, and consequently reducing frictional engagement between the wire and the plates to a minimum. Means to be presently described is provided for varying the space between the fingers 49 to accommodate different diameters of wire. It will be noted, referring to Figs. 1 and 2, that no engagement between the periphery of the coil 12 and the plates 35 and 36 is possible, since the periphery of the roller 43 is outside the adjacent fingers 49 of the plates and engages the coil, but at the same time a minimum space is provided therebetween so that the wire 13 is guided right up to its winding point. The wire guide plates 35 and 36 at their right sides (Fig. 2) extend up close to the periphery of the sheave 48, the plate 35 extending around the underside of the sheave 48 for a short distance, while the plate 36 is cut off on a vertical line at the left side of the sheave 48 as indicated at 50.

Mounted on the plate 35 at the right of the point 50 of the plate 36 is a spring clip 53 bearing at its free end against the plate 36. The purpose of cutting off the plate 36 at the point 50 and mounting the clip 53 upon the plate 35 in

engagement with the plate 36 is to facilitate the threading of the wire 13 between the plates after passing it around the sheave 48, which is accomplished by threading the wire between the clip 53 and the plate 36 to position the wire as shown in Fig. 6. This threading of the wire over the clip 53 also prevents the wire, when slackness occurs upon completion of a winding operation, when the wire from the supply is severed, from dropping from between the plates.

Referring particularly to Fig. 5, the wire guide plate 35 has fixed thereto an internally threaded collar 54, into which is threaded an outwardly and internally threaded collar 55, slotted at its outer end and abutting at its inner end the inner surface of the plate 36. When the collar 55 is rotated in one direction in the collar 54, its inner end engaging the plate 36 serves to flex the plates 35 and 36 outwardly from each other to widen the space therebetween, particularly the space between the fingers 49 in accordance with the diameter of the particular wire 13, and when the collar 55 is rotated in a reverse direction the space between the fingers 49 may be decreased. Threaded into the collar 55 is a screw 56 for clamping the plates 35 and 36 in their set position after an adjustment, the screw being first threaded outwardly in the collar 55 when it is necessary to make an adjustment of the space between the fingers 59.

In the operation of winding a coil 12 by means of a winding machine which includes the strand or wire distributor 17 hereinbefore described, the end of the wire 13 is led from a usual tensioned supply source (not shown) to and over a sheave 57 journaled on the bracket 16, to and under the sheave 48, between the clip 53 and the guide plate 36 and into the space between the plates 35 and 36, and thence the space between the fingers 49 thereof and secured in a usual manner to the revolvable core 11 upon which the wire is wound to form the coil 12, the flanged roller 43 resting on the periphery of the core and straddling the wire. During the rotation of the core 11 in the direction of the arrow (Fig. 2) and simultaneously with the reciprocation of the traversing rod 10, the wire 13 is advanced by the rotation of and wound upon the core in close adjacent helices, first in one direction and then in a reverse direction to form successive layers, and as the diameter of the coil 12 gradually increases with each successive layer of wire wound upon the core, the flanged roller 43 moves freely upwardly. A movement of the roller 43 upwardly carries with it the bar 20 and the attached parts forming the wire distributor 17. During this upward movement of the bar 20 the pivotal brake shoe 27 slides upon the associated stationary surface of the bracket arm 19 which is still maintained in frictional contact therewith by means of the spring pressed plunger 29 engaging the raised portion 28 of the shoe.

Upon completion of the winding of a coil 12 the wire 13 is severed and the operator grasps the hand screw 33 and slides the wire distributor 17 upwardly upon the arms 19 of the bracket 16 and then releases it, the braking action of the shoe 27 being effective to maintain the wire distributor 17 in position above the wound coil. The finished coil 12 is then removed from the winding machine and a core 11 for the next coil to be wound is mounted in position. Thereafter the operator slides the guide 17 downwardly into operative position by merely pressing downwardly upon the hand screw 33, the roller 43 con-

tacting with the periphery of the core 11 ready for the winding of the next coil. After insuring that the end of the wire 13 is still properly threaded between the guide fingers 49 of the 5 plates 35 and 36 and is secured to the core 11, the coil winding operation proceeds as hereinbefore described.

Although the construction of the strand or wire distributor illustrated in the drawing and hereinbefore described may be used to advantage in connection with the winding of a particular type of 10 electrical coils, it should be understood that its use may have a broader application, and furthermore it should not be limited to the particular 15 construction shown, except as defined by the appended claims.

What is claimed is:

1. In a strand material distributor, the combination with a rotatable element on which 20 strand material is to be wound, of a distributor including a carriage reciprocable longitudinally of the rotatable element, a member operatively associated with the periphery of the rotatable element and movable outwardly therefrom in 25 response to the increasing diameter of the body of strand material wound on the element, said member movable upon the carriage in a rectilinear path, strand material guiding and distributing elements positioned adjacent the periphery of the rotatable element and movable with said member, and means for maintaining 30 said member in any of a plurality of different positions.

2. In a strand material distributor for coil 35 winding machines including means for supporting and rotating a core on which strand material is to be wound, a carriage reciprocable longitudinally of the core, a sliding member resting upon the periphery of the core and movable upwardly in response to the increasing diameter 40 of the body of strand material wound on the core, said carriage having slideways upon which said sliding member may move only in a single definite path, strand material guiding and distributing 45 elements positioned adjacent the periphery of

the core and movable with said member, a spring 50 pressed brake mounted in said member and constantly engaging a surface of said carriage for maintaining the member in any of a plurality of different positions.

3. In a strand material distributor for coil winding machines including means for supporting and rotating a core on which strand material is to be wound, a carriage reciprocable longitudinally of the core, a slideable member engaging the periphery of the core and movable outwardly in response to the increasing diameter of the body of strand material wound on the core, said carriage having slideways adapted to receive said member for movement only in a single definite path, strand guiding and distributing fingers positioned adjacent the periphery of the core and movable with said member, means carried by said member for constantly applying friction between the carriage and the member 55 for maintaining the latter in any of a plurality of different positions, and means for varying the degree of friction between the carriage and the member.

4. In a strand material distributor for coil 100 winding machines including means for supporting and rotating a core on which strand material is to be wound, a carriage reciprocable longitudinally of the core, a slideable member engaging the periphery of the core and movable outwardly 105 therefrom in response to the increasing diameter of the body of strand material wound on the core, said carriage having slideways adapted to receive said member for movement only in a single definite path, strand guiding and distributing 110 fingers positioned adjacent the periphery of the core and movable with said member, a brake shoe pivotally mounted on said member for engaging a surface of said carriage for maintaining the member in any of a plurality of different 115 positions, and a spring pressed plunger mounted in said member in operative engagement with said brake shoe to constantly urge said shoe into engagement with the surface of the carriage.
